UNITED STATES PATENT OFFICE

WILLIS T. BURNS, OF PLAINFIELD, NEW JERSEY

CATHODE-LOADING MACHINE

Application filed June 16, 1927. Serial No. 189,203.

The invention relates to apparatus for handling plates or flat slabs.

- While not limited thereto the embodiment of the invention illustrated is adapted for use in transferring cathode plates. In practice, such cathode plates are frequently transported in piles on a car to a position in which a charging machine unloads them and inserts them in the refining furnace.
- 10 The machine illustrated is adapted to receive bundles of plates from an overhead crane and to hold them while supported on edge and means are provided for turning the stack or bundle of plates through an angle 15 of substantially 90 degrees so that they can be deposited flatwise in a pile on suitable cleats or angle irons carried by a flat car adapted to carry the plates into juxtaposition to a refining furnace so that the arm 20 of the charging machine can engage the pack of plates from the underside.

The invention will be fully understood from the following specification when read in connection with the accompanying drawings and the features of novelty will be pointed out with particularity in the appended claims. In the drawings—

Fig. 1 is a side elevation of a loading machine embodying my invention and showing a flat car adapted to receive the plates carried by the loading machine;

Fig. 2 is a fragmentary view of a portion of Fig. 1 with certain parts shown in the position to which they are moved to transfer the plates from the loading machine to the flat car;

Fig. 3 is a plan view on a reduced scale of the movable platform shown in Fig. 1;

40 Fig. 4 is an enlarged central longitudinal section showing the reversible operating mechanism for actuating the movable platform;

Fig. 5 is a plan view of Fig. 4 with parts omitted and parts shown in section;

Fig. 6 is a vertical transverse section on line 6—6 of Fig. 4;

Fig. 7 is a vertical transverse section on line 7—7 of Fig. 4;

50 Fig. 8 is a detail section showing the con-

struction of the stationary platform of the loading machine;

Fig. 9 is a plan view of one corner of said stationary platform;

Fig. 10 is a section on line 10—10 of Fig. 9 through the discharge lip of the stationary platform.

Referring in detail to the drawings, A designates a suitable flat car arranged to travel on tracks *a*. The floor *a'* of the flat car has secured thereto a series of transversely extending angle irons one of which is shown at *a*². The upper edges *a*³ of the angle irons collectively serve as a support for a pile or stack of plates as indicated at P in Fig. 2. The plates held on the flat car in this way are supported in such manner that there is a space between the top of the floor *a'* and the underside of the lowermost plate. This permits the arm of a suitable charging machine to pass below the pile of plates so that when lifted it can remove them.

My improved loading machine indicated as a whole at B is arranged to receive the plates P as shown in their upright position in Fig. 1 and to deposit them in a flatwise position as shown in Fig. 2.

The loading machine includes a substantially rectangular frame 10 made up of channel irons or similar structural shapes, the frame being provided with suitable bearings for supporting axles 12 and 14 carrying wheels 16 for movably supporting the machine on tracks 18.

Supported above the frame 10 by means of suitable upright struts 20 is a fixed or stationary platform 22 and steps 24 are provided to enable workmen or operators to reach the platform, the steps being braced to the frame 10 as indicated at 26.

A movable platform 28 is supported above the stationary platform 22 on arms 30 which are secured to and move with a shaft 32 mounted in suitable bearings carried by the under frame of the machine. Arms 34 formed integrally with or secured to the arms 30 extend at an angle slightly greater than a right angle from the arms 30 and serve in one position to support a pile of plates on their edges as indicated in Fig. 1. That is,

the edges of the plates P rest on the movable platform 28, the flat part of the first plate resting against the upright arm 34. Secured to the shaft 32 which carries the arms 30 and 34 is a worm wheel sector 36, the teeth of which mesh with a worm 38 carried by a shaft 40 mounted in fixed bearings 42. At its lower end this shaft 40 carries a bevel gear 44 which meshes with a similar gear 46 secured to a transversely extending shaft 48 journalled in bearings 50 secured to a plate 52 carried by the frame 10. This plate supports the channels 54 to which is secured a casting 56 carrying bearings for the worm shaft 40.

10 The shaft 48 at its opposite ends carries sprocket wheels 58 and 60 from which are trained sprocket chains 62 and 64 which, respectively, engage sprockets 66 and 68 carried at the opposite ends of a transversely extending shaft 70 mounted in bearings 72 supported on the frame plate 52.

15 The shaft 70 carries a spline 74 which engages a suitable groove formed in the sleeve 76 slidingly mounted on said shaft 70. This sleeve has keyed thereto a pair of friction discs 78 and 80 which are so arranged that either disc may be brought into operative frictional contact with a drive cone 82. The friction drive cone 82 is carried by a shaft 30 84 which is connected by a suitable coupling 86 with the armature shaft 88 of a driving motor 90. The oppositely arranged discs 78 and 80 as shown in Fig. 5 are in neutral position; that is, they are both clear of the drive cone 82. These discs are adapted to be alternately engaged with the driving cone so as to reverse the direction of rotation of the shaft 48 which in turn will, of course, reverse the direction of the worm 38 which drives or rocks the movable platform 28. For shifting the sleeve 76, I provide a collar 92 which is loosely journalled on the end portion of the sleeve 76. The collar 92 is retained by means of a nut 94 which abuts a shoulder 96 formed on the sleeve so as not to bind said collar. Standing upwardly from the collar 92 are arms 98 which support a transversely extending pin 100 to which is pivoted a link 102 which in turn is connected by a suitable pivot pin with the free end of an arm 104 of a shift lever 106 pivoted on a stud 108 carried in suitable brackets 110 secured to one of the channels 54 forming part of the frame work of the machine.

20 The fixed platform 22 of the loading machine is formed in two sections bolted together near the center by studs 114 indicated in Fig. 8. The marginal edges of the platform are flanged as indicated at 116 and the entire upper surface of the platform is pitched or canted to a slight extent so as to permit any accumulation of solution which drips from the plates handled to drain toward the outlet spout 118 formed at one rear corner of the platform 22. A flange 120 ex-

tends around the opening 122 formed in the fixed platform 22 so as to prevent any accumulated liquid from finding its way to the operating mechanism located below said fixed platform. The opening 120 (Fig. 7) in the platform 22 is provided to permit the passage therethrough of the operating rack 36 and the arms 30 which support the moving or swinging platform 28.

25 The swinging platform 28 is provided with raised bearing pads 124 which are preferably serrated as indicated at 126 in Fig. 1 to prevent slippage of the plates P when they are in the vertical position of Fig. 1.

30 In operation it will be readily understood that the plurality of plates deposited edge-wise on the movable platform 28 can be readily supported in a substantially vertical position against the upright arms 34. The platform, it is clear, will be held against overturning because of the self-locking connection of the worm 38 and worm sector 36. The loading machine can be moved along suitable tracks 18 to any desired position, for example, into proximity to a flat car as indicated in Fig. 1. Upon reaching the flat car the operator will shift the lever 106 so as to bring the appropriate friction disc 78 or 80 into engagement with the friction drive cone 82 so as to cause the movable platform 28 to be swung to the position of Fig. 2 so as to deposit the plates on the upstanding angle irons a^3 carried by the flat car. The loading machine will then be backed away from the flat car so as to withdraw the arms 34 from the space below the stack of plates P resting on the angle irons a^3 . The shift lever 106 will then be again actuated to return the movable platform 28 to the substantially horizontal position of Fig. 1 so that the machine is in condition to receive another supply or bundle of plates from the overhead crane.

35 Of course, it is clear that, if desired, the reverse operation may be effected so as to unload plates from a flat car onto the loading machine.

40 Instead of rocking the shaft 32 by means of a worm and worm wheel segment and related mechanism as shown, I may substitute in place thereof a spur gear segment and pinion driven through suitable spur gear and reduction gear direct connected to an electric motor equipped with an automatic cut-off switch, said switch being adapted to stop the motor at any predetermined position of travel of the movable platform. Various other speed reducing means may be used between the motor and the movable platform.

45 While I have described with great particularity certain specific details of the embodiment of the invention illustrated, it is not to be construed that I am limited thereto since various modifications or substitution of equivalents may be made by those skilled in

the art without departing from the invention as defined in the appended claims.

What I claim is:

1. A machine of the class described including a mobile frame having pivotally supported thereon a movable platform having grooves formed therein adapted to receive the lower edges of a plurality of plates, means on said platform for holding said plates in substantially upright positions, means for rocking said platform so as to deposit said plates flatwise on a suitable support and a fixed platform above said rocking means.
2. A loading machine of the character described including a mobile frame, a supporting shaft carried thereby, a platform supported thereon, plate holding arms extending radially outward from said shaft and substantially or approximately at right angles to the surface of said platform, and means for turning said shaft through an angle of approximately 90 degrees and a fixed platform secured to said frame above said turning means adapted to shield the latter.
3. A loading machine of the character described including a mobile frame, a plate supporting platform, L-shaped members secured thereto, a shaft-carrying said members, a worm sector secured to said shaft, a worm for turning the latter, a motor and mechanism between the motor and said worm for reversing the direction of rotation of said worm and a fixed platform below the plate supporting platform adapted to catch the drip from the plates handled.
4. A loading machine of the character described including a mobile frame, a platform fixedly secured above said frame, a shaft supported by the frame below said fixed platform, a movable platform normally supported on said shaft in a position above said fixed platform, plate holding arms supported by said shaft, motor driven means carried by said frame below said fixed platform adapted to turn said shaft through an angle of approximately 90 degrees.
5. A loading machine of the character described including a frame, a shaft supported thereby carrying a movable platform and upright arms, a gear sector secured to said shaft, a worm coacting therewith and reversible driving mechanism operatively connected with said worm, a fixed platform in a plane between said movable platform and said driving mechanism.
6. A loading machine of the character described comprising a wheeled frame, a fixed platform secured thereto, a swingable platform adapted to be normally supported in substantially horizontal position above said fixed platform, a shaft located below said fixed platform for supporting said swingable platform, a worm sector secured to said shaft, a worm meshing with said sector and secured

to a vertically disposed shaft supported by said frame, a jack shaft carrying a bevel gear and sprockets operatively connected with said vertical shaft, a second jack shaft carrying sprockets and friction drive discs, chains connecting the sprockets on said jack shafts, a motor driven cone arranged to co-operate with said friction drive discs and means for engaging either of said discs with said motor driven cone.

In witness whereof, I have hereunto signed my name.

WILLIS T. BURNS.
